UNITED STATES PATENT OFFICE.

ALBERT JEFFERS, OF LYNN, MASSACHUSETTS.

MACHINE FOR MOLDING, ROUNDING, AND CHANNELING SOLES OF BOOTS AND SHOES.

Specification forming part of Letters Patent No. 83,172, dated October 20, 1868.

To all whom it may concern:

Be it known that I, ALBERT JEFFERS, of Lynn, in the county of Essex and State of Massachusetts, have made an invention of a new and useful Machine for Molding, Rounding, and Channeling the Soles of Boots and Shoes previous to being applied to the uppers; and I do hereby declare the following to be a full, clear, and exact description thereof, due reference being had to the accompanying drawings, making part of this specification, and in which—

Figure 1 is a front elevation, Fig. 2 is a side elevation, Fig. 3 a vertical central and longitudinal section, and Fig. 4 a vertical and transverse section, of the machine comprising the subject of my present invention. Fig. 5 is a plan, Fig. 6 an inner end elevation, and Fig. 7 an outer end elevation, of the "head-stock," so-called, of the machine, or that portion of it carrying the channeling and rounding tools or cutters, to be hereinafter described. Fig. 8 is a face view of cam; Fig. 9, a side elevation of the clutches, to be hereinafter described. Fig. 10 is a bottom view of the segmental block, to be hereinafter described.

The object of my present invention is to embrace or comprise in one machine mechanism for performing the operations of "molding," "channeling," and "rounding" the soles of boots and shoes, as they are technically termed, the former consisting in forming or shaping the surface or area of the sole to fit the bottom of a last, the second in cutting a groove or channel for reception of the stitching or sewing in securing the sole to the upper of the boot, while the latter consists in cutting around the edge of the sole in order to conform it to the outline of the last to which it is to be applied.

For the purpose of clear elucidation and explanation of the machine, and to enable persons skilled in the craft to which it appertains to make and use such machine, the following description of its construction and operation may be divided into two parts, the first being that for molding the sole, and the second that of channeling and rounding such sole.

In the various figures of the drawings before mentioned as accompanying this specification and illustrating my invention like figures indicate like parts.

Beginning with the molding portion of the machine, the reader, by referring to these drawings, will see that the frame of the machine is shown by the letter A as of a suitable size and form to receive the operative parts, to be herein-after described, its general form in front elevation being similar to that of the well-known McKay sewing-machine, now in extensive use for sewing together the sole and upper of a boot or shoe, and to which my present invention is a very valuable adjunct. The frame A, in its general construction, is composed of two legs or standards, a a, united at top by two horizontal bars or rails, b b, upon which is fixed a broad, flat table or platform, c.

The driving-shaft of the machine is shown at d as properly supported and revolving in boxes e e affixed to the lower part of the standards a a, before mentioned, the driving-shaft being disposed parallel to and in alignment with the table c, before mentioned, such shaft being provided between the standards with a drum or pulley, f, for driving a portion of the machinery, and having affixed to its rear extremity a fast and loose pulley, g h, the former of which is the driving-pulley of the shaft d, a proper fly-wheel, i, being affixed to such shaft.

The upper part of the main standard or double goose-neck a of the machine is provided at its rear side and at the center thereof with a box-bearing, j, for supporting an upright sliding shaft, k, such shaft k depending from the center of a cross-head, l, disposed parallel to and above the standard a, such cross-head being connected to a second cross head or bar, m, disposed parallel to it and between the table c, and supported upon guides a⁵ a⁶, the two cross-heads being connected by upright rods n n, as represented, and forming therewith a rectangular sliding frame, B, the stiffness of the lower cross-head, and consequently the strength or power of the frame, being regulated by an arched spring, o, applied to the upper surface of such cross-head, the tension of such spring being regulated by screws and nuts properly applied to the two.

The sliding frame B is maintained in its highest altitude under all conditions, except those hereinafter named, by means of a heavy weight, p, disposed below the table c, and communicated with the lower cross-head, m, by

chains q q , which pass over pulleys r r , revolving upon studs affixed to the outer sides of the rails b b , before mentioned.

To the under side of the lower cross-head is pivoted a tripper or hooked bar, s , the hook t of which acts in conjunction with a cam-groove, u , of the form shown in Fig. 8 of the drawings, and upon the front face of a flat circular disk, v , fixed upon the driving-shaft d and in rear of the tripper s .

A molding-block, w , is affixed by a swiveling or ball-and-socket joint to the lower end of the upright shaft k , before mentioned, the under or bearing surface of this molding-block being of like shape with a supporting-bed or forming-last to be presently referred to, such molding-block, as well as the forming-last, corresponding in form to the tread of the last upon which the boot is to be made.

The molding-block is to be secured to the shaft k in such manner as to allow of a slight movement in any direction, in order to insure its perfect adjustment to the upper surface of the forming last or die before alluded to. This forming last or bed is shown at x as supported by means of posts y y' upon the upper surface of a dovetailed sliding carriage or bar, z , which slides in a dovetail slot or opening, a^2 , cut longitudinally and centrally of the table c of the machine, the upper surface of such block being furnished with a series of pointed studs, b' b'' , &c., for retaining the sole firmly in place thereon while undergoing the rounding and channeling process.

The rear part or standard, y' , of the forming last x extends through a slot, c' , of the sliding carriage z and below such carriage, while through the lower end of the post, and below the carriage, and in alignment therewith, is screwed a long male screw, d' , cut upon a horizontal shaft, e' , such shaft being supported at each end in bearings f' f'' depending from the under side of the table c of the machine, and so as to revolve freely therein. This screw is for effecting reciprocating or backward and forward movements of the forming or supporting bed x , which is accomplished by revolving alternately in opposite directions, such revolution of the screw being effected as follows: Upon the rear end of such screw is fixed or formed a collar, g' , while upon opposite sides of such collar, and loosely enveloping the screw, are two semi-clutches, h' h'' , such semi-clutches being formed as shown in Fig. 10 of the drawings—that is, with their outer peripheries composed of a pulley, i' , and a grooved disk, j' or j'' .

Around the pulley of the foremost clutch h' and the drum f of the driving-shaft before mentioned an endless belt, k' , travels, while around the pulley of the foremost clutch h'' and the said drum f a cross-belt, l' , travels, the two belts thus serving to revolve the two clutches in opposite directions from each other.

A shipper for actuating or reversing the clutch is shown at c as composed of a long bar or rod, m' , sliding in bearings n' n'' made

immediately below the bearings f' f'' of the shaft e , before mentioned, such shipping-bar being provided with stops o' o'' , formed upon it and disposed upon opposite sides of its bearings n' , one or both of such stops being adjustable, and their position with respect to the bearing n' being so disposed or maintained as to regulate the length of movement of the sole-supporting bed x . This shipping-lever is connected with the clutches h' h'' by means of two forked uprights, p' p'' , which straddle the groove-disks of such clutches, as shown in Fig. 10 of the drawings, it being understood that the construction of the semi-clutches h' h'' and the collar j' of the screw-shaft e' are substantially the same as that of ordinary clutches now in constant use, and with which all mechanics are familiar. The above constitutes the portion of the machine designed for molding the sole.

We now come to that portion of the machine designed for rounding and channeling, and which is constructed as follows:

A circular dovetailed groove, q' , is formed within the upper surface of the table c of the machine or within an extension or base thereof, such groove being concentric with the heel and toe of the forming or supporting last or bed x when in the extreme of its movement, the outline of such groove being in this instance the form of a circle or appertaining thereto.

Within the groove q' is disposed a segmental dovetailed supporting-block, s' , and to the upper surface of this segmental block is affixed the inner end of a lever plate or carriage, u^3 , the outer end of such lever-plate being provided with a handle, w , for causing a semi-revolution of such plate and its mechanism about the heel and toe of the last at the proper times. A second flat plate or carrier, v' , is disposed upon the top of the lever-plate u^3 , and maintained in place thereon by two ledges or ribs, w' w'' , formed upon such plate u^3 , and so as to allow of backward and forward movements of the carrier v' thereupon, a zigzag or other proper-shaped spring, v^4 , being placed between the outer end of the carrier v' and the handle of the plate u^3 , and serving by its extensile power to force such carrier inward. Still another and third grooved plate, x' , is swiveled at its inner end to the upper surface, and at the inner end of the carrier v' , and so as to be capable of swinging horizontal movements thereon, the said plate x' being furnished at its inner end with two friction-pulleys, y^2 y'' , which bear against the edge or outline of the supporting-bed x .

A carriage, z' , is disposed upon the upper surface of the plate x' , and sliding within and guided by its groove, which is dovetailed, such carriage z' being forced inward and toward the supporting-bed x by two coiled springs, a^2 a^3 , placed upon opposite sides thereof, one extremity of such spring being affixed to the inner end of the swiveling plate x' , the opposite

extremity of the spring being attached to the outer end of the carriage z' , or to the lower ends of two arms, b^2 , depending from a horizontal shaft, c^2 , supported in bearings d^2 d^2 affixed to the rear end of the carriage z' , this shaft c^2 being provided with a handle, e^2 , for partially rotating it, the object of applying the springs a^2 a^3 to the shaft c^2 in this manner being to release the action of the springs upon the carriage or to bring them into play, as occasion requires.

The carriage z' is furnished at each end with two upright posts, z' z' , such posts being for the support of a tool-carrier, g^2 , which slides freely thereon, such tool-carrier being depressed toward the carriage z' by coiled springs applied to the two, as shown in the drawings, and also by a long bent spring, i^2 , one end of which is applied to the shaft c^2 , before mentioned, its free end being carried forward and resting upon the upper surface of the said tool-carrier g^2 .

The handle e^2 of the shaft c^2 is brought into a vertical position and confined to one of the posts f^2 by a hook, j^2 , applied thereto, which presses against the spring i^2 and forces it upon the tool-carrier with considerable pressure, at the same time partially revolving the shaft c^2 , and by retracting its arms b^2 also extends the spring a^3 and causes them to exert their power to advance the carriage z' , and with it the tool-carrier g^2 .

The carriage z' carries at its inner end, and between and immediately in advance of the friction-rollers y^2 an upright knife or rounding-tool, k^2 , the object of this knife or rounding-tool being to cut the sole close to the edge of the supporting-last x . Furthermore, a horizontal rocker-shaft, b^2 , is supported in bearings made in the lower part of the tool-carrier g^2 , such rocker-shaft being given an upward and right-angular bend, n^2 , and carrying a cutter-head, m^2 , such cutter-head being swiveled to the shaft l^2 , or its bend, in order to allow of such cutter-head being turned upward out of contact with the sole at certain times. This cutter carries the channeling-tool shown at o^3 in the drawings.

As the construction and operation of the channeling-tool are fully explained in Letters Patent of the United States issued to William Duchemin and myself for an improved mode of channeling soles, a detailed description of its form and use is not considered necessary or pertinent part of this specification. I would remark, however, that the channeling-tool is to be applied to the cutter-head in such manner and in combination with a movable guide as to allow of its position with respect to the cutter-head and guide being changed or varied in order to regulate the depth of the channel to be cut, and for other purposes.

I will call the reader's attention to the fact that the segmental supporting-block s' has a segmental slot, p^2 , cut a short distance in one end of its under surface, as shown in Fig. 11

of the accompanying drawings, the end of this slot being provided with a recess or hole, q^2 , for reception of two locking bolts or pins, which play within orifices made in the table c of the machine, these locking-bolts being connected with the revolving screw and with the movements of the supporting-bed x in such manner or so operated by a suitable device as to alternately lock into the depression q^2 of the block s' after such block and its mechanism have completed the circuit of the heel or toe of the bed x , and serve to lock such block and its mechanism firmly in position while the longitudinal movement of the sole is taking place by the action of the revolving screw, it being understood and will be apparent that the sides of the sole are trimmed and grooved by the action of the screw forcing such sole against the cutting and grooving tools, while the heel and toe of the sole are cut by the hand of the operator forcing such tools in a circular path about the heel and toe of the bed x .

I would call attention to the fact that the table c is or may be applied to the form of the machine in any adjustable manner, and also that the molding-block w and the bed or die x are also applied in a movable manner, in order to allow of their ready removal for the substitution of different sizes, and would also state, although the intelligent reader will probably understand, that these two portions of the machine are directly opposite each other.

The operation of the above-described machine, which, though voluminous, is necessary to a complete understanding of its construction, is as follows: The sole-blank or piece of leather, having previously been moistened by immersion in water, is to be placed upon the forming last or bed, or upon the top of its points b , &c., the position of the forming-bed being as shown in the drawings—that is, the extreme inward point of its movement—the head-stock of the machine also being in position at the right of the operator, as shown in the drawings. The sole-blank or piece of leather to be manipulated is to be placed upon the upper surface of the forming-bed x or upon its points b , &c., and the plate z' and cutter-head g^2 being retracted or removed from proximity to the bed. The frame B is then to be depressed by a person's hand and until the hook t of the tripper s is caught by or takes into the cam-groove u of the disk v , such groove being of a scroll form, as shown in Fig. 8 of the drawings. A revolution of this cam-groove has the effect of lowering the frame b , and with it the molding-block w , which is pressed forcibly upon the sole, and, by clamping it between such molding-block and the forming last or bed x with great pressure, serves to conform the sole to the shape of the last, the points of which serve to securely hold it thereto. As the cam-groove completes its revolution the hook of the tripper s frees itself from such groove and allows the gravity of the weight p , or any other suitable mechanical con-

trivance capable of producing the same result, to elevate the frame b , and with it the molding-block w , to its normal position, or that shown in the drawings. Next the plate z' and cutter-head g^2 are to be permitted to be forced forward by their respective springs, and so that the knife k^2 impinges against the edge of the bed x , and with a channeling-tool, o^2 , pressed down upon the upper surface of the sole and near its edge with considerable pressure, the friction-rollers f^2f^2 , as before observed, bearing against the edge of the bed x and serving to keep the knife k^2 parallel to or closely up against the said edge of the bed. The shipping-bar m' is now pushed in to its farthest extent, which has the effect of throwing the clutch h' into connection with the collar g' of the screw e in the direction shown by the arrow in Fig. 4 of the drawings, or in a like direction with that of the driving-shaft of the machine. This revolution of the screw has the effect of advancing the bed x , and with it the sole, which, by being drawn along in contact with the knife k^2 , is cut away closely up to the edge of the bed, the channeling-tool o^2 at the same time taking into the upper surface of the sole and forming the channel for reception of the stitching. The continued revolution of the screw advances the sole and the bed x until a stud or bar, s , affixed to the lower part of the post y' of such bed strikes against the inner stop, o' , of the tripper-bar m' , when such shipping-bar is also advanced until the clutch h is removed from contact with the collar g and the sole and its bed allowed to remain stationary, the locking-pin r^2 being at this point depressed and leaving the segmental block s free to revolve partially within the groove q' , the stop of the shipping-lever being so arranged with respect to the size of the bed x that its movements shall be stopped at such a time as to leave the knife k^2 at the beginning of the circular or toe portion of such bed x . The operator now seizes the handle u' , and by turning the segmental block s' within its groove causes the head-stock, and consequently the rounding and channeling tools, to describe a semicircular path about the toe of the sole and the bed x , and thus cut and channel such toe of the sole in the same manner as with the side before described. The head-stock is now upon the opposite side of the sole, or at the left of the operator, who now pulls out the shipping-bar m' to its farthest extent. This forces the clutch h^2 into contact with the collar g' of the shaft e' , such shaft e' , by means of the cross-belt l' , being revolved in an opposite direction to that first described, this revolution of the screw causing a retrograde movement of the sole and its supporting bed, or toward the rear of the machine, while simultaneous with the beginning of this retrograde movement the opposite locking-pin, r^2 , is forced into the recess q^2 of the segmental block s' in the same manner as at first, and locks the head-stock and its tools in the position last mentioned.

The screw continues to revolve and force the bed x rearward until the rear standard or post, y' , of the bed x comes in contact with a tripping-block, x' , fixed to the under side of the sliding carriage z , and by forcing such tripping-block into contact with the clutch h' forces it and its fellow clutch rearward until the latter is removed from connection with the collar g' and the screw allowed to revolve without further actuating the bed x , the pin r at this point being lowered and the segmental block s' being left free to revolve, it being, of course, understood that during the last or rearward movement of the bed x and the sole the latter has been rounded and channeled in the same manner as upon the opposite side of such bed. The operator now seizes the handle u' and causes the head-stock and its cutting and channeling tool to describe a semicircular path about the heel of the sole, and trimming and channeling the heel of such sole, thus having made the entire circuit of such sole and made a complete channel for reception of the stitching, this last movement of the head-stock bringing it into its original position at the right of the operator and of the machine. The plate z' and the tool-carrier g^2 are now to be removed from contact with the sole, or into the position shown in the drawings, and the sole removed from the bed x and a new blank substituted. The sole thus removed will be found to have received a perfect impress of the bed x , as well as to have been cut to the outline of such bed, and with an endless channel cut in it.

I would call the reader's attention to the fact that a deflector or fender, u^2 , is applied to the front standard of the machine, and between it and the cam-disk v , before mentioned, and disposed with respect to the latter in such manner that upon descent of the hooked tripper s its hook shall be deflected into the cam-groove u , and upon being released from the cam-groove the tripper shall pass up against the outside of the said deflector u^2 until it reaches its highest position, or nearly so, the inner terminus of the bottom of the cam-groove being inclined outward for the purpose of effecting such a result.

The advantages of the machine comprising the subject of my present invention consist, as before prefaced, mainly in the fact that, as the three operations are combined in one machine and the work performed in one complete movement or circuit of the working parts of such machine, the number of machines is reduced to one-third the number now required to do the same work, with a consequent diminution of the amount of capital required to conduct the business. It also diminishes to about that extent the size of the room occupied by such machines, with a consequent diminution in the amount expended for rent of such rooms or building, the number of operators being reduced to about one-third the number heretofore required, making a saving

of expense of great magnitude. The work is also performed by the machine in the most thorough and perfect manner.

Having thus described the construction, operation, and advantages of my present invention, what I claim as being novel and original with myself, and desire to secure by Letters Patent of the United States of America, is as follows:

1. The combination, in an organized machine, of mechanisms for molding and for channeling and rounding a sole, under the arrangement and for operation substantially as herein set forth.

2. As a means of molding a sole, the combination of the molding-block w and the supporting last or bed x , the former being supported by and swiveled to the sliding frame b and operated by the cam-groove u , or its equivalent, and the latter provided with a series of points or spurs, b b' , &c., the whole being substantially as hereinbefore referred to and explained.

3. For actuating the movements of the sliding frame b , the combination of the weight or its equivalent, applied as described, with the cam-groove and the tripper s , essentially as explained.

4. In combination with the cam-groove and tripper last mentioned, the employment of the deflector n^2 , applied and operating in manner and for the purpose as before explained.

5. For effecting the alternate movements of the screw, and, as a consequence, the reciprocating movements of the bed, the employment of the two semi-clutches h h' , operating in connection with a collar, g' , revolved by the endless belts K' L' , and adjusted and controlled

by the shipping-bar m' and its adjuncts, for the purpose as hereinbefore referred to and explained.

6. In combination with the last-described arrangement of parts, the employment of the locking-bolts r^2 , actuated by a suitable device, the purpose of such bolts being as before explained.

7. The head-stock of the machine, as composed of the segmental dovetailed block S' , the supporting lever plate or carriage t' , the plate or carriage v' , the swiveling plate x' , the carriage z' , and the tool-carrier g^2 , under the general combination and arrangement as before alluded to and described.

8. The mode of applying the carriage z' to the swiveling plate x before described—that is, by means of the coiled springs a^3 a^3 , applied to the shaft as explained, the latter being provided with the lever or handle, in manner as before set forth, and in combination with the springs a^3 a^3 , shaft e^2 , and handle e^2 , the employment of the bent spring i^2 , in manner and operating as before explained.

9. Applying the cutter-head n^2 to its supporting-carriage in such manner as to turn it into a vertical position or to remove it from contact with the bed x , essentially as described.

10. In combination with the swiveling plate x , the employment of the friction-rollers y^2 y^2 for the purpose of maintaining the cutting-knife k^2 parallel to the edge of the bed x , as before explained.

ALBERT JEFFERS.
